UNITED STATES PATENT OFFICE.

MORRIS DAVIS, OF LOS ANGELES, CALIFORNIA.

BRANDING DEVICE.

Application filed March 14, 1927. Serial No. 175,281.

This invention relates to a branding device and particularly pertains to a branding device of the electrically heated type.

The primary object of the invention is to provide a branding device in which the branding indicia may be readily changed from time to time as occasion may require.

Another object is to provide an electrically heated branding device in which the branding element is so formed and mounted as to insure proper heating thereof.

Another object is to provide a branding device which is especially applicable for use in branding motor vehicle tires to designate the date of sale thereof, and accordingly comprehends the provision of an effective means whereby the branding indicia may be changed from day to day in accordance with changing dates.

With the foregoing objects in view together with such other objects and advantages as may subsequently appear the invention resides in the parts and in the combination and construction of parts hereinafter described and claimed, and illustrated by way of example in the accompanying drawings in which:

Fig. 1 is a view of the branding device as seen in side elevation;

Fig. 2 is a view in section and end elevation as seen on line 2—2 of Fig. 1 in the direction indicated by the arrows;

Fig. 3 is a detail in horizontal section as seen on the line 3—3 of Fig. 1 with portions removed to show the heating element;

Fig. 4 is a plan view of the lower end of the branding device;

Fig. 5 is a detail in section as seen on the line 5—5 of Fig. 1;

Fig. 6 is a detail in transverse section as seen on the line 6—6 of Fig. 1;

Fig. 7 is a perspective view of a fragmentary portion of one of the branding elements.

Referring to the drawing more specifically 8 and 9 indicate spaced side members of a yoke carried on a handle 10. Revolvably mounted on a shaft 11 carried by the yoke is a series of wheels or rollers 12, 13 and 14 having peripheral studs or teeth 15. Mounted on the outer end portions of the members 8 and 9 is a shaft 16 preferably formed of insulating material on which is revolvably mounted a series of thin metallic sleeves 17, 18 and 19 disposed in alignment with the wheels 12, 13 and 14 respectively. A series

of thin steel ribbon bands 20, 21 and 22 pass around the rollers 12, 13 and 14 respectively and around their associated sleeves 17, 18 and 19. These metal bands constitute branding elements and for this purpose are provided with suitable indicia 23 which are formed by providing openings in the bands having the outline of the desired character so that when the metal bands are heated, as will be hereinafter described, and applied to effect a branding action, the indicia or characters will be embossed on the object branded. By thus forming the branding band a more even heating thereof is effected than where the characters are raised on the branding element as ordinarily practiced.

The bands are formed with indents or openings 23' spaced apart longitudinally thereof which are engaged by the teeth 15 on the rollers 12, 13 and 14 to effect a positive connection between the bands and rollers. Bearing against each of the rollers is a spring pressed brake 24 mounted on a spring arm 25 carried by a bar 26 extending between the members 8 and 9 which brakes serve to hold the rollers against free rotation and also act to position the rollers and hold them against turning with the bands disposed so that the indicia on adjacent bands will be aligned across the underside portions of the sleeves 17, 18 and 19 as shown in Fig. 4. To this end the brakes 24 are of such length that when disposed between adjacent teeth 15 the ends of the brakes will abut against the contiguous faces of the adjacent teeth as particularly shown in Fig. 2.

In practice the band 20 is provided with indicia designating years such as '27, '28, etc.; the band 21 is provided with indicia corresponding to the number of days in the month, and the band 22 is provided with indicia corresponding to the number of months in the year. It is obvious however that any suitable characters may be provided on the several bands as occasion may require.

As a means for heating the branding elements an electrical conductive and resistance element 29 is arranged in a recess or chamber 30 formed in the shaft 16; the terminals of which element connect with studs 31 and 32 leading through an insulating cap 33 and adapted to be connected into an electric circuit through the medium of the usual socket connection. The chamber 30 opens to the under side of the shaft 16 so as to expose the sleeves 17, 18 and 19 to the heating ele-

ment 29. Mounted on the lower end of the member 9 is a fixed branding plate 34 which extends on a plane with the portion of the branding bands passing beneath the sleeves 5 17, 18 and 19. This branding plate 34 extends across the chamber 30 containing the heating element 29 so that it will absorb heat from the latter. The branding plate 34 may be demountable so that various indicia may 10 be readily provided to precede the indicia carried by the branding bands.

In the operation of the invention the bands 20, 21 and 22 are adjusted, if necessary, to bring the desired indicia in alignment at the lower end of the device, which is effected by manually rotating the bands on the rollers 12, 13 and 14 and on the sleeves 15 17, 18 and 19. On directing an electric current through to the heating element 29 the lower portions of the bands will be heated 20 through the sleeves and the branding plate 34 will also be heated so that on applying the lower end of the device to the surface 25 to be branded said surface will be burned by the heated metal surrounding the open indicia thereby forming a brand with enclosed characters surrounded by a burned field.

I claim:

1. In an electrically heated brander, a 20 branding band formed with indicia openings, and means for electrically heating the band.
2. In a branding device, a metallic band formed with indicia openings and an electric heating element around which said band is 35 passed contiguous thereto but spaced therefrom.
3. In a branding device, a metallic band formed with indicia openings, an electric heating element around which said band is 40 passed contiguous thereto but spaced therefrom, and a mounting for said band permitting adjustment of the latter to dispose various portions thereof adjacent said heating element.
4. In a branding device, a metallic band 45 formed with indicia openings, a roller and a turnable sleeve supporting said band, and a heating element encompassed by the sleeve.

5. In a branding device, an electrical heating element, a plurality of sleeves encircling 50 said element, a band passing around each of said sleeves, formed with branding indicia, and wheels around which said bands pass operable to permit adjustment of the bands to dispose various indicia thereon contiguous 55 said sleeves.

6. In a branding device, an electrical heating element, a plurality of sleeves encircling 60 said element formed with branding indicia, wheels around which said bands pass operable to permit adjustment of the bands to dispose various indicia thereon contiguous 65 said sleeves, and means engageable with said wheels for opposing rotation thereof.

7. In a branding device, an electric heat- 65 ing element, a fixed branding plate arranged to be heated by said element, a plurality of metallic bands provided with branding indicia, and revoluble supports for said bands; said bands being arranged with portion 70 thereof contiguous to said heating element.

8. In a branding device, a metallic band formed with openings constituting indicia, a mounting for said band on which the band may be moved to present the various indicia 75 thereon to a branding position, and means for heating a portion of the band surrounding an indicia opening disposed in the branding position.

9. An electrically heated brander embodying a shaft formed with a heating chamber opening to one side thereof, an electrically conductive and resistance element in said chamber, a metallic sleeve revoluble on said shaft a portion of which extends over said 85 chamber, and an indicia carrying band passing over said sleeve in contact therewith, whereby heat will be conducted from the sleeve to the band.

10. In a branding device, a series of indicia bearing metallic bands, a support on 90 which said bands are carried, and an electrical heating element arranged to transmit heat to said bands.

MORRIS DAVIS.
